SANITARY TOOTHPICK DISPENSER

Carl A. Witt, Detroit, Mich.

Application June 28, 1939, Serial No. 281,680

5 Claims. (Cl. 312—84)

This invention relates to dispensers and in particular to sanitary toothpick dispensers adapted to pay out one toothpick at a time without clogging.

5 The principal object of the invention is to provide an extremely simple sanitary dispenser for round toothpicks and the like which will pay out but one toothpick at a time and in which the dispensing element is adapted to hold one 10 or more toothpicks after being paid out ready to be manually removed from the said dispensing means.

Another object of the invention is to provide an extremely simple, inexpensive to manufacture, 15 sanitary dispenser for toothpicks and the like having but a single movable dispensing element which will pay out round toothpicks one at a time, the dispensing element being adapted to hold at least one toothpick after having been paid 20 out while one or more other toothpicks are paid out without interfering with the paying out of toothpicks subsequent to the paying out of the first toothpick.

Other objects of the invention will become 25 apparent by reference to the following detailed description taken in connection with the accompanying drawing, in which:

Fig. 1 is a side elevational view of a sanitary toothpick dispenser embodying the invention with 30 a portion thereof broken away showing the pivotal mounting of the dispensing element employed.

Fig. 2 is an end elevational view of the dispenser disclosed in Fig. 1.

35 Fig. 3 is an enlarged sectional view taken on the line 3—3 of Fig. 1 showing the dispensing element in its normal position.

Fig. 4 is an enlarged cross sectional view similar to Fig. 3 showing the dispensing element pivoted manually to a position in which it receives 40 a toothpick from the hopper.

Fig. 5 is an enlarged plan view with the cover removed showing the particular shape of hopper employed.

45 Referring now to the drawing wherein like numerals refer to like and corresponding parts throughout the several views, the sanitary toothpick dispenser disclosed comprises, in general, a hopper 10 preferably moulded of thermo-plastics 50 or the like supported on a pair of legs 11 formed integral with the ends of the said hopper and located inwardly therefrom between which a dispensing element designated by the numeral 12 is pivotally mounted about an axis longitudinal with respect to the said hopper 10 on pins

13 disposed through the lower portion of the said legs 11. The legs 11 supporting the hopper 10 are preferably secured to a suitable base 14 by rabbeting the same therein as indicated in the drawing. A cover 15 having a depending 5 peripheral edge 16 is frictionally engaged over the top of the said hopper 10.

The said hopper 10 has vertical sides 17 and ends 18 and a sloping bottom 19 which terminates into a pair of laterally spaced vertically 10 depending aprons 20 oppositely curved along their longitudinal axes complementary to the curvature of the side of a toothpick to be dispensed from the said hopper. The bottom of the said depending aprons 20 are formed to a vertical 15 curve complementary to the curvature of the side of a toothpick to be dispensed from the said hopper. The lateral space between the said depending hopper bottom aprons 20 is equal to at least three and preferably four times the diameter of a toothpick to be dispensed from the dispenser plus a slight clearance to avoid jambing. The foregoing relationship between the size and 20 shape of the hopper 10 and the toothpicks to be dispensed therefrom is important inasmuch as, 25 after long experiment, it has been found that any material deviation from the above causes the dispenser to become jammed during operation.

The dispensing element 12 is composed of a longitudinally disposed shaft 21 integral with 30 which is moulded laterally spaced dispensing segments 22 and 23 which extend radially upward from the said shaft 21 to close the bottom of the hopper 10 between the longitudinally disposed depending aprons 20 thereof, the front portion of 35 the segments 22 and 23 being notched as indicated in Figs. 2, 3 and 4 for the purpose herein-after described in detail. The said shaft 21 has an aperture 24 longitudinally therethrough into which mounting pins 13 disposed through suitable apertures in the legs 11 are pressed.

The front end of the dispensing segment 23 is preferably enlarged at 25 and is cored to receive an operating arm 26 onto the end of which a suitable operating knob 27 is fixed. The weight 45 of the said knob 27 is such as to normally maintain the dispensing element 12 and the segments 22 and 23 thereof rotated to the position indicated in Figs. 2 and 3 wherein the unnotched portion of the segments 22 and 23 is positioned 50 directly under the depending aprons 20 of the hopper 10, in which position the segments 22 and 23 of the dispensing element 12 support the toothpicks 28 in the hopper 10. A stop 29 suitably located on the segment 23 of the dispensing 55

element 12 prevents the said dispensing element 12 from rotating too far under the gravity influence of the operating knob 27, see Fig. 3. In its lifted position the operating knob 27 contacts the front side of the hopper 10 and serves as a stop to permit the segments 22 and 23 of the dispensing element 12 to rotate when the said operating knob is lifted until the carrier notches 30 therein become positioned slightly greater than the diameter of one toothpick inward from the inner side of the front depending apron 20 of the hopper 10, see Fig. 4.

By reference to Fig. 4 it will be observed that the rearward portion of the carrier notches 30 in the segments 22 and 23 of the dispensing element 12 are disposed substantially vertical when the operating knob is lifted to the toothpick receiving position, however, the forward portion of the said carrier notches 30 slopes forwardly 20 downward when the dispensing element 12 is permitted to drop by gravity to the toothpick dispensing position shown in Fig. 3 wherein a toothpick received by the said segments 22 and 23 in the carrier notches 30 thereof rolls out of the said carrier notches into the dispensing notches 31 in the segments 22 and 23. It is preferable that the said dispensing notches 31 in the segments 22 and 23 are large enough to receive at least two toothpicks. The said dispensing notches 31 being so disposed as to present to the user of the dispenser toothpicks paid out from the hopper 10 to the dispensing notches by the carrier notches each time the operating knob 27 is fully lifted to the position shown in Fig. 4 from its normal position shown in Fig. 3 and permitted to drop back to its normal position shown in Fig. 3.

The said dispensing notches 31 in the dispensing segments 22 and 23 are shaped reentrant so as to prevent any toothpick once received therein from rolling back into the carrier notches 30 and fouling the paying out of toothpicks from the hopper 10 by gravity into the said carrier notches 30. If more toothpicks are paid out of the hopper 10 into the carrier notches 30 by repeated lifting of the operating knob 27 than the capacity of the dispensing notches 31 then excess toothpicks paid out will merely fall from the dispensing element 12. A suitable spacer bar 32 is preferably provided integral with and laterally between the upper rear portion of the segments 22 and 23 to maintain them in rigid radial alignment.

Although the novel sanitary toothpick dispenser has been shown and described as manufactured of moulded plastics, obviously it may be constructed of metal or other suitable material by those skilled in the art.

Although but one specific embodiment of the invention has been disclosed and described in detail, it is obvious that many changes and modifications may be made in the size, shape, arrangement and detail of the various elements of the invention without departing from the spirit thereof, and it is not intended to limit the scope of the invention other than by the terms of the appended claims.

I claim:

1. In a sanitary toothpick dispenser, a hopper having a slot in the bottom thereof, means supporting said hopper, an apron depending from said hopper each side of said slot, a dispensing element composed of a longitudinally disposed shaft journaled on said hopper supporting means for arcuate movement on an axis parallel to and below the said slot in said hopper and a pair of

laterally spaced dispensing segments extending upwardly from said shaft into substantial contact with said depending aprons, the segments of the said dispensing element each having a carrier notch and a dispensing notch in the periphery thereof, the said carrier notches being located to receive but one toothpick at a time when the said dispensing element is moved arcuately under said hopper slot to a toothpick receiving position and shaped to permit the toothpick carried therein to gravitate to the said dispensing notches when said dispensing element segments are moved arcuately forward with respect to the said hopper slot to a toothpick dispensing position, and an operating handle on said dispensing element for moving the said dispensing element arcuately on its axis to and from the toothpick receiving position from and to the toothpick dispensing position.

2. In a sanitary toothpick dispenser, a hopper having a slot in the bottom thereof, means supporting said hopper, an apron depending from said hopper each side of said slot, the said aprons being curved along their oppositely disposed inner faces and along the bottom thereof complementary to the curvature of the side of a toothpick to be dispensed, a dispensing element composed of a longitudinally disposed shaft journaled on said hopper supporting means for arcuate movement on an axis parallel to and below the said slot in said hopper and a pair of laterally spaced dispensing segments extending upwardly from said shaft into substantial contact with said depending aprons, the segments of the said dispensing element each having a carrier notch and a dispensing notch in the periphery thereof, the said carrier notches being located to receive but one toothpick at a time when the said dispensing element is moved arcuately under said hopper slot to a toothpick receiving position and shaped to permit the toothpick carried therein to gravitate to the said dispensing notches when said dispensing element segments are moved arcuately forward with respect to the said hopper slot to a toothpick dispensing position, and an operating handle on said dispensing element for moving the said dispensing element arcuately on its axis to and from the toothpick receiving position from and to the toothpick dispensing position.

3. In a sanitary toothpick dispenser, a hopper having a slot in the bottom thereof at least slightly greater in width than the diameter of three toothpicks to be dispensed therefrom, means supporting said hopper, an apron depending from said hopper each side of said slot, the said aprons being curved along their oppositely disposed inner faces and along the bottom thereof complementary to the curvature of the side of a toothpick to be dispensed, a dispensing element composed of a longitudinally disposed shaft journaled on said hopper supporting means for arcuate movement on an axis parallel to and below the said slot in said hopper and a pair of laterally spaced dispensing segments extending upwardly from said shaft into substantial contact with said depending aprons, the segments of the said dispensing element each having a carrier notch and a dispensing notch in the periphery thereof, the said carrier notches being located to receive but one toothpick at a time when the said dispensing element is moved arcuately under said hopper slot to a toothpick receiving position and shaped to permit the toothpick carried therein to gravitate to the said dispensing notches when said dispensing element

- segments are moved arcuately forward with respect to the said hopper slot to a toothpick dispensing position, and an operating handle on said dispensing element for moving the said dispensing element arcuately on its axis to and from the toothpick receiving position from and to the toothpick dispensing position.
5. In a sanitary toothpick dispenser, a hopper having a slot in the bottom thereof at least slightly greater in width than the diameter of three toothpicks to be dispensed therefrom, means supporting said hopper, an apron depending from said hopper each side of said slot, a dispensing element composed of a longitudinally disposed shaft journaled on said hopper supporting means for arcuate movement on an axis parallel to and below the said slot in said hopper and a pair of laterally spaced dispensing segments extending upwardly from said shaft into substantial contact with said depending aprons, the segments of the said dispensing element each having a carrier notch and a dispensing notch in the periphery thereof, the said carrier notches being located to receive but one toothpick at a time when the said dispensing element is moved arcuately under said hopper slot to a toothpick receiving position and shaped to permit the toothpick carried therein to gravitate to the said dispensing notches when said dispensing element segments are moved arcuately forward with respect to the said hopper slot to a toothpick dispensing position, and an operating handle on said dispensing

element serving as a counterweight means for normally maintaining the said dispensing element in its dispensing position therefor.

5. In a sanitary toothpick dispenser, a hopper having a slot in the bottom thereof, means supporting said hopper, an apron depending from said hopper each side of said slot, a dispensing element composed of a longitudinally disposed shaft journaled on said hopper supporting means for arcuate movement on an axis parallel to and below the said slot in said hopper and a pair of laterally spaced dispensing segments extending upwardly from said shaft into substantial contact with said depending aprons, the segments of the said dispensing element each having a carrier notch and a dispensing notch in the periphery thereof, the said carrier notches being located to receive but one toothpick at a time when the said dispensing element is moved arcuately under said hopper slot to a toothpick receiving position and shaped to permit the toothpick carried therein to gravitate to the said dispensing notches when said dispensing element segments are moved arcuately forward with respect to the said hopper slot to a toothpick dispensing position, and an operating handle on said dispensing element for moving the said dispensing element arcuately on its axis to and from the toothpick receiving position from and to the toothpick dispensing position, the said dispensing notches being reentrantly formed sufficiently to prevent toothpicks received therein from rolling back into the carrier notches when said dispensing element is moved arcuately to its receiving position from its dispensing position.
